UNITED STATES PATENT OFFICE.

JOHN F. O'CONNOR AND STERLING M. WILLIAMS, OF DAVENPORT, IOWA.

EARTH-SCRAPER.

SPECIFICATION forming part of Letters Patent No. 296,044, dated April 1, 1884.

Application filed June 30, 1883. (No model.)

To all whom it may concern:

Be it known that we, JOHN F. O'CONNOR and STERLING M. WILLIAMS, of Davenport, in the county of Scott and State of Iowa, have invented a new and useful Improvement in Earth-Scrapers, of which the following is a full, clear, and exact description.

Our invention relates to improvements in earth-scrapers; and it consists in the peculiar construction and arrangement of the parts, as hereinafter more fully set forth, and pointed out in the claims.

Reference is to be had to the accompanying drawings, forming a part of this specification, in which similar letters of reference indicate corresponding parts in both the figures.

Figure 1 is partly a side elevation and partly a longitudinal sectional elevation of our improved scraper, and Fig. 2 is a perspective view.

To a box or scoop of the scraper, made in two parts, *a* and *b*, which are separated transversely at about the middle of the scraper from front to back, and connected at *c* by pivots, on which they can swing to open and close the bottom, we pivot the catches *d* at *e* to the hind part, *b*, for hooking onto the studs *f* of the front part, *a*, for fastening the scraper together. The catches are arms of a bar, *g*, extending along the back of the part *b* of the scraper over the lever *h*, by which they are released at any time when the scraper is to be dumped, the lever being extended upward and backward from the scraper suitably for being lifted by an attendant standing behind the machine when it is desired to dump the scraper. When lever *h* swings down and the two parts of the scraper close together, the lever drops a little lower than the rod *g*, allowing it to close the catches *d* on the studs *f* by gravity. We suspend the scraper by chains *i* and *j* from the frame *k* of a truck, the chains *i* being connected to the front ends of the sides of the scraper by bars *l*, pivoted at *l'* to the scraper, and chains *j* being connected to link-bars *m*, that are pivoted to the sides of the part *b* a little in advance of the back of the scraper, and the same distance from the middle joint of the scraper, so that the load will dump it self by reason of the preponderance of weight

between the link-bars *l* and *m*, and the chains all adjusted for length, so that the load will balance back of them a little, to facilitate the raising of the front end of the scraper a little higher than the back end when it is desired to carry the load, to avoid spilling the load out of the mouth of the scraper. The connection by the pivots *n* also facilitates the swinging of the scraper forward when it is to be dumped, as will be seen in Fig. 2. The pivots *n* and *o*, also the pivots *e* of the catches *d* are supported outside of the bar *m* and catches by a bar, *o*, suitably fastened to the side of the scraper for the purpose. The suspending-chains *i* *j* pass over rollers *p* in the truck-frame, and extend to and are connected to segmental pulleys *q* and *t* on a shaft, *u*, supported in brackets *v* above the top of the truck-frame, and having a long lever, *w*, extending upward when the scraper is down in the working position, and connected at its free end with a cord, *x*, extending back to a drum, *y*, located at the back end of the truck-frame, and having lever-arms *z*, for turning it to pull down the lever *w* and raise the scraper. The segmental pulleys *q*, to which the chains *i* of the front end of the scraper are connected, are eccentric to the shaft *u*, and have longer sweep than the other pulleys, *t*, to which chains *j* are connected, for the purpose of raising the front open end of the scraper higher than the back end, to retain the load while being carried on the truck. The drum *y* also has an eccentric extension, *a'*, whereon the cord *x* winds at the beginning of the movement, to have greater sweep and quicker action at the beginning of the operation.

The pulleys *p* are mounted on the truck-frame by supporting-brackets *b'*, that are adjustably attached to the frame by bolts *d'*, that are adjustable along the slots *c'* of the frame to shift the scraper, so that the amount of the load carried on the necks of the horses through the tongue *f'* may be regulated at will, and the bolts *g'*, connecting the cranked axle *h'* to the frame, are fitted in slotted holes, (dotted, Fig. 1,) to allow of altering the balance of the frame on the wheels *i'*.

For applying the draft to the scraper, we suspend the evener *j'* as low under the tongue

as the top of the scraper, or thereabout, by the frame k' , and hitch the team to it, and also hitch the scraper to the lower end of the frame by the chains l' , which are attached to draft-bars l' , also pivoted to the scraper at l' , which causes the draft to be applied directly to the scraper, so that when it is let down into the ground for taking its load it is practically independent of the wheels. From the eye n' a rod, which hooks into said eye, will extend to the end of the pole for the loading team to be hitched to it.

In the use of large scrapers it may be desirable to employ the power of a team of horses to raise the scraper by the lever w , for which we propose to have a hook, m' , attached to the lever, whereto a chain may be hitched, said chain extending down under a pulley on the axle, inside of the crank, and thence to the under side of the pole f' and to the end, where the team for raising the scraper may be hitched to said chain to pull down the lever w and raise the scraper. The drum y has a ratchet, o' , and pawl p' , to hold lever w when down.

Having thus described our invention, what we desire to claim and secure by Letters Patent is—

1. The combination, with the scraper $a b$, suspended by chains $i j$ from the truck, of the guide-pulleys p , segmental pulleys $q t$ on a shaft, u , the segmental pulleys q , to which the front end of the scraper is connected, being eccentric to the shaft u , and having a longer sweep than the pulleys t , and the adjusting-lever w , substantially as described. 35

2. The combination, with the lever w , segmental pulleys $q t$, the former being arranged eccentrically to the shaft u , and having a longer sweep than the pulleys t , and chains $i j$, of the drum y , having an eccentric extension, a' , 40 cord x , levers z , and a scraper suspended from a truck, substantially as described.

3. The combination, with a truck, of a scraper consisting of two parts, a and b , jointed together, and provided with fastening-catches d , connecting-bar g , and lever h , and being suspended from the truck by the chains $i j$, substantially as described. 45
